UNITED STATES PATENT OFFICE.

GEORGE A. AMSDEN, OF LITTLETON, MASSACHUSETTS, ASSIGNOR TO THE LAMSON COMPANY, OF NEWARK, NEW JERSEY, A CORPORATION OF NEW JERSEY.

LOCKING DEVICE FOR CARRIERS.

1,071,018.

Specification of Letters Patent. Patented Aug. 26, 1913.

Application filed February 28, 1908. Serial No. 418,221.

To all whom it may concern:

Be it known that I, GEORGE A. AMSDEN, of Littleton, in the county of Middlesex and State of Massachusetts, have invented certain new and useful Improvements in Locking Devices for Carriers, of which the following is a specification.

My invention relates to improvements in locking devices for carriers and is especially adapted for use in carriers such as are used in cable carrier apparatus for the transmission of cash etc.

The object of this invention is to supply a simple and effective locking device which will positively lock the cover of the carrier closed and prevent the accidental opening of the same when rounding the turn or in transit.

In the accompanying drawings is illustrated a construction embodying my invention in which,—

Figure 1 is a top plan view of a cable cash carrier showing the cover locked closed. Fig. 2 is a similar view to Fig. 1, showing locking device released and carrier about to be opened by the operator. Fig. 3 is a perspective of the carrier with cover open. Figs. 4, 5 and 6 are details of the locking mechanism hereinafter described.

Like letters of reference refer to like parts throughout the several views.

A represents an ordinary cable cash carrier having a cover B hinged at C and adapted to be held open by a spring D. Pivoted at F in the cup shaped depression H on the outside of the cover B is a lock lever E having a handle G for operating the same and carrying a latch J adapted to engage the lip K on the body of the carrier A to lock the cover B closed and to clear the lip K when the lever E is opened, to release and permit the cover to open.

The cover B is cut away at L to allow the cover to pass the lip K.

M is a stud fixed to the under side of lever E and adapted to operate in the slot N in cover B to limit the movement of said lever.

O represents a flat spring secured at one end to the under side of cover B and having a rib P adapted to coöperate with stud M to prevent the accidental displacement or movement of the lever E.

The fiber plate R is secured to the bottom of the shell of the carrier A by screws T and

operate in conjunction with the plate S to 55 guide the carrier along the tracks.

To open the carrier the operator moves the handle G throwing the lock lever E to the limit of its outward movement causing the stud M to ride over the spring rib P and 60 moving the latch J out of coöperation with the lip K (see Fig. 2) when the cover B will be released and thrown open by the spring D. The cash may now be placed in the carrier and the cover closed and the operator may 65 lock the same by throwing the lever E inward until the stud M has passed the spring rib P and the latch J has passed underneath and engaged the lip K holding the cover securely closed.

The rib P prevents the lock lever E from being thrown open by the movement of the carrier in transit positively preventing the accidental release of the contents.

Having thus described my invention and 75 set forth a construction embodying the same, what I claim as new and desire to secure by Letters Patent of the United States, is:—

1. In a carrier, a receptacle, a lip projecting inwardly from the side wall of said receptacle, a cover hinged to said receptacle having its edge cut away to clear said lip, a latch pivoted to the outer face of said cover and adapted when operated at one end to cause its opposite end to engage said lip, a 80 stud projecting from the under side of said latch and engaging a slot in said cover to limit the movement of said latch, and means for holding the latch in both its adjustments.

2. In a carrier, a receptacle, a lip projecting inwardly from the side wall of said receptacle, a cover hinged to said receptacle having its edge cut away to clear said lip, a latch pivoted to the outer face of said cover 85 to engage said lip, a stud projecting from the under side of said latch through a slot in the cover to limit the movement of the catch, and a spring on the inner face of said cover bearing on said stud to hold the catch 95 in its adjustments.

3. In a carrier, a receptacle, a lip projecting inwardly from the side wall of said receptacle, a cover hinged to said receptacle having its edge cut away to clear said lip 100 and provided with a depression adjacent to the cut-away part of its edge, a latch having a portion centrally pivoted in said depre-

sion to the cover and adapted when operated at one end to cause its opposite end to engage said lip, and an operating handle extending from said circular portion and in such relation to the cut away portion of the edge that it will lie entirely within the outlines of the receptacle when the latch is closed.

4. In a carrier, a receptacle, a lip projecting inwardly from the side wall of said receptacle, a cover hinged to said receptacle having its edge cut away to clear said lip and provided with a depression adjacent to the cut-away part of its edge, a latch pivoted in the depression of the cover to engage said lip, a lever forming part of said latch projecting outside of said depression, a stud projecting from the under side of said lever through a slot in said cover to limit the movement of the latch, and a spring secured to the inner face of said cover having a rib to engage said stud to hold said lever in the adjustments of the latch.

5. In a carrier, a receptacle having a part projecting inwardly from the side wall of the receptacle, a cover hinged to the receptacle so that when closed it will be substantially entirely within the outer edge of the receptacle and said cover having its edge cut away to clear said inwardly projected part when the cover is closed, a latch pivoted to the outer face of the cover to engage said part, and means for holding the latch in both of its adjustments.

6. In a carrier, a receptacle, a cover hinged to the receptacle so that when closed it will be substantially entirely within the outer edge of the receptacle, a latch on the outer face of the cover and adapted to engage the receptacle to lock the cover to the receptacle, and means for holding the latch in its cover locking adjustment, said means adapted to automatically hold said latch in said adjustment by the mere movement of said latch into said adjustment.

7. In a carrier, a receptacle, a cover hinged to the receptacle so that when closed it will be substantially entirely within the outer edge of the receptacle, a latch pivoted to the outer face of the cover and adapted to engage the receptacle to lock the cover to the receptacle, and means for holding the latch in both of its adjustments.

8. In a carrier, a receptacle, a cover hinged to the receptacle so that when closed it will be substantially entirely within the outer edge of the receptacle, a latch pivoted to the outer face of the cover and adapted to engage the receptacle to lock the cover to the receptacle, and means for automatically holding the latch in both of its adjustments.

9. In a carrier, a receptacle, a cover hinged to the receptacle so that when closed it will be substantially entirely within the outer edge of the receptacle, a latch pivoted

to the outer face of the cover and adapted to engage the receptacle to lock the cover to the receptacle, and yielding means for permitting the latch to move in both directions and to hold the latch in both its adjustments. 70

10. In a carrier, a receptacle, a cover hinged inside of the receptacle so that when it is closed it will be entirely within the outer edge of the receptacle, a latch on the outer face of the cover and adapted to engage the receptacle to lock the cover to the receptacle, a stud projecting from the under side of said latch through a slot in the cover which limits the movement of the latch, and a spring on the inner face of the cover bearing on said stud and having a rib adapted to engage said stud to hold said latch in both of its adjustments. 75 80

11. In a carrier, a receptacle, a cover hinged inside of the receptacle so that when closed it will be entirely within the outer edge of the receptacle, a pivoted latch on the outer face of the cover and adapted to engage the receptacle to lock the cover to the receptacle and swinging outside the body of the box to open the cover, a stud projecting from the under side of said latch through a slot in the cover which limits the movement of the latch, and a spring on the inner face of the cover bearing on said stud and 85 having a rib adapted to engage said stud to hold the latch in both of its adjustments. 90 95

12. In a carrier, a receptacle, a cover hinged to said receptacle so that when closed it will be substantially protected by the edge of the receptacle, a combined latch and handle for said cover comprising a member movably mounted upon the outside of the cover and having both its latching part and its handle forming part upon said outer side 100 of said cover, said receptacle provided at a point substantially contiguous to its said edge with means for engaging said latching part whereby to lock the cover in its closed position, said handle forming part of said 105 member adapted to be moved out beyond said edge for unlocking said cover and when so disposed facilitating the re-closure of said cover by the hand of the operator and providing a handle for such purpose, and 110 resilient means for frictionally holding said member in its cover latching position. 115

13. In a carrier, a receptacle, a cover hinged to said receptacle so that when closed it will be substantially protected by the edge of the receptacle, a combined latch and handle for said cover comprising a member movably mounted upon the outside of the cover and having both its latching part and its handle forming part upon said 120 outer side of said cover, said receptacle provided at a point substantially contiguous to its said edge with means for engaging said latching part whereby to lock the cover in its closed position, said handle forming part of 125 130

said member facilitating the re-closure of said cover by the hand of the operator and providing a handle for such purpose, said cover being recessed upon its said outer side 5 and the latching part of said member being disposed within said recess.

14. In a carrier, a receptacle having a latch engaging part, a cover hinged to said receptacle, a latch carried by said cover 10 adapted to engage said part to lock the cover in its closed position, and means for holding the latch in both its cover locking and its unlatching position, according to the disposition of said latch, whereby when the 15 latch is in its latching position the cover cannot become inadvertently opened, said latch overhanging the edge of said cover when in its unlatching position, and providing a handle for facilitating the closure of 20 said cover, said holding means retaining said latch when disposed in the position last mentioned, definitely in said position, whereby to prevent its inadvertent displacement with respect to said cover when being 25 used as a handle.

15. In a carrier, a receptacle having a

latch engaging part, a cover hinged to said receptacle, a latch carried by said cover adapted to engage said part to lock the cover in its closed position, and means for holding the latch in both its cover locking and its unlatching position, according to the disposition of said latch, whereby when the latch is in its latching position the cover cannot become inadvertently opened, said 30 latch, when in its unlatching position, providing a handle for facilitating the closure of said cover, said holding means retaining said latch when disposed in the position last mentioned, definitely in said position, 35 whereby to prevent its inadvertent displacement with respect to said cover when being used as a handle.

In testimony whereof, I have signed my name to this specification in the presence of 40 two subscribing witnesses, this 21st day of February, A. D. 1908.

GEORGE A. AMSDEN.
